FREDERICK G. KEYES, OF EAST ORANGE, NEW JERSEY, ASSIGNOR TO COOPER HEWITT ELECTRIC COMPANY, OF HOBOKEN, NEW JERSEY, A CORPORATION OF NEW JERSEY.

ELECTRIC LAMP.

1,206,333.

Specification of Letters Patent. Patented Nov. 28, 1916.

Application filed March 6, 1914. Serial No. 822,863.

To all whom it may concern:

Be it known that I, FREDERICK G. KEYES, a citizen of the United States, and resident of East Orange, county of Essex, State of New Jersey, have invented certain new and useful Improvements in Electric Lamps, of which the following is a specification.

In certain applications numbered 811,002 and 811,003, both filed on the 8th day of January 1914, I illustrate and disclose tungsten lamps in which filaments of tungsten capable of carrying current of from 3 to 50 amperes constitute the illuminants, whereby the filaments are less fragile than those in ordinary commercial use and whereby also, on account of the lower applied potential, the lamps escape certain of the limitations imposed by the usual commercial supply voltages. In the application bearing the lower serial number the filament is wound into spiral form and has its terminals connected through tubular seals to the outside circuit. In the other application the coiled or spiral filament is supported in such a manner as to form angles which may result in a star shape or some other shape adapted to concentrate the light given off by the filament when the lamp is in operation.

In my present invention I make use in certain cases of a crimped ribbon filament, thereby providing for the dispersion from the filament of an increased illumination with the same expenditure of electrical energy as in other lamps.

The same result will be accomplished in a lesser degree by the use of a plain ribbon of tungsten or the like in place of a crimped ribbon.

In the drawings which accompany and form a part of this specification Figure 1 shows a section of crimped metal ribbon; Fig. 2 is a vertical section of one of my lamps, a portion of which is shown in full lines; Fig. 3 is a bottom view of the filament shown in Fig. 2; Figs. 4 and 5 illustrate different arrangements of a ribbon and Fig. 6 is a detail view.

In the drawings, 1 is a globe for one of my lamps and 2 is a tungsten filament, here shown in the form of a crimped ribbon, located approximately at the center of the globe. The filament is attached at its ends by means of loops, 5, 5, of tungsten wire lead wires 3, 3, of nickel-steel. The tungsten wire may be replaced by a wire of

molybdenum, tantalum, or other refractory metal, and a convenient mode of attachment is to form a loop or bend in the metal wire, bring it up against the side of the ribbon at the ends thereof and then crimp the ribbon down upon the wire. Similar rods are shown at 4, 4, the same being provided with tip portions of tungsten or other refractory metal in the form of wire which are sealed to nickel-steel rods and may be bent around at their outer ends so as to surround completely or partially the central portion of the tungsten ribbon and support the same along its middle. The leads 3, 3, and the rod, 4, pass through a disk or diaphragm, 6, of aluminum lying within a tubular extension, 7, of the globe 1 and being arranged just above a shoulder, 8, near the bottom of said extension. The object of the diaphragm 6 is to shut off from the tubular extension 7 and from the lamp seals, presently to be described, near the upper end of said extension, all unnecessary heat. The diaphragm 6 forms the support for the leads 3, 3, and the anchor rod 4 is supported by the said diaphragm through intermediate connections.

What I have called the inner leads 3, 3, are provided with sockets 12, 12, suitably sealed thereto and having any convenient depth. Into these sockets extend copper leads 9, 9, which form mechanically a part of the seals of the lamp. The rods, 9, 9, pass through platinum tubes 10, 10, constituting the main conducting portions of the lamp seals. On the outer ends of the tubes 10, 10, are placed iron caps 11, 11, which are welded to the tubes 10, 10, and the rods 9, 9, by means of an oxy-acetylene flame. The external leads may be copper wires 13, 13, fused or soldered to the caps 11, 11, as shown.

It will be observed that the seals are made within a reentrant portion of the extension 7, whereby the danger of fracture from mechanical causes is reduced. The tubes 10, 10, are sealed within the said reentrant portions. The entire interior of the lamp is thus sealed off from exposure to the external air and a structure is provided which admits of the safe and continuous application thereto of currents ranging from 3 to 50 amperes. In this way lamps of exceedingly high candle power are obtainable without unduly shortening the life of the lamps.

It will be observed that a rod, 60, of glass

is secured to the bottom of the reentrant portion and after being carried down to a point near the bottom of the extension 7 is provided with shoulders, 61 and 62, which hold the diaphragm, 6, in place. The central portion of the part, 60, may be hollow to receive material for absorbing water vapor or oxygen from the inside of the extension, 7, although these features do not necessarily form a part of the present invention and the details are omitted.

The mode of connection between one of the inner leads 3, and the aluminum diaphragm 6 is illustrated in Fig. 2. An opening being made in the diaphragm at the proper point the tube of copper and iron, surrounded by a tube 14 of quartz is passed through the diaphragm and the entire inner space is then packed with a suitable cement, 15, such as might be formed by the mixture of ground silica and sodium silicate. This prevents the contact of the inner leads with the aluminum diaphragm and thus obviates the danger of short circuiting between said leads. By similar construction the anchor rod 4 is supported in the diaphragm and insulated therefrom and from the inner leads 3, 3.

The means for inserting the diaphragm 6 into place between the shoulders 61 and 62

are illustrated in Fig. 6. An opening shaped somewhat like a key-hole is made in the diaphragm as shown at 65, and the wider part of the opening is large enough to pass over the shoulder 62. As soon as it has 35 reached this point, the diaphragm is pushed along so that the narrow portion of the opening 65, surrounds a reduced part 64, of the rod 60. In this position the disk is retained firmly between the shoulders 61 and 62 and the diaphragm is properly placed within the extension 7.

I claim as my invention:

1. In a tungsten lamp, a luminant of tungsten in the form of a crimped ribbon 45 and leads connected with the terminals of said ribbon.

2. In a tungsten lamp, a luminant of tungsten in the form of a crimped ribbon having its ends brought into proximity to 50 each other and forming a filament having angles at intervals and leads connected with the terminals of the ribbon.

Signed at New York, in the county of New York and State of New York, this 3rd 55 day of March, A. D. 1914.

FREDERICK G. KEYES.
